UNITED STATES PATENT OFFICE.

HARRY THAYER KINGSBURY, OF KEENE, NEW HAMPSHIRE.

DESIGN FOR A TOY-SPADE-HANDLE MEMBER.

SPECIFICATION forming part of Design No. 35,332, dated November 26, 1901.

Application filed October 15, 1901. Serial No. 78,754. Term of patent 14 years.

To all whom it may concern:

Be it known that I, HARRY THAYER KINGSBURY, a citizen of the United States, residing at Keene, in the county of Cheshire, State of New Hampshire, have invented a new and original design for a Toy-Spade-Handle Member, of which the following is a description, reference being had to the accompanying drawings, and to the letters of reference 10 marked thereon.

My invention relates to a new and original design for a toy-spade-handle member; and it consists in a member of a spade-handle of the shape and configuration shown.

15 In the drawings which illustrate the invention, Figure 1 is a perspective view of a spade-handle member embodying the design, and Fig. 2 is a cross-section.

In the drawings, A represents the lower 20 part of the spade-handle member, which from about the central portion a tapers down on either side toward the lower end b and from

said wider portion a tapers upwardly to a point c, where it joins the downwardly and upwardly bent portion B, which portion B is 25 convex, as shown. The upper end of the portion B is expanded, its upper edge being formed, substantially, into a circular plate C of greater diameter than the width of the part B. 30

The leading feature of the design consists of a toy-spade-handle member of the above-described shape and configuration.

Having thus described my invention, what I claim, and desire to secure by Letters Patent, is—

The design for a toy-spade-handle member; substantially as shown and described.

In testimony whereof I affix my signature in presence of two witnesses.

HARRY THAYER KINGSBURY.

Witnesses:

W. L. MASON,
E. L. SALISBURY.
